UNITED STATES PATENT OFFICE

WILLARD F. RICHARDS, OF DEPEW, NEW YORK, ASSIGNOR TO THE GOULD COUPLER COMPANY, OF NEW YORK, N. Y., A CORPORATION OF MARYLAND

COUPLER

Application filed April 26, 1927. Serial No. 186,781.

This invention relates to couplers and, more particularly, to a coupler of the same general character as that disclosed in my application, Serial Number 107,150, filed May 6, 1926, now Patent No. 1,789,659, dated January 20, 1931.

The principal object of my invention, generally considered, is the provision of a car coupler with a bottom-operated lock, there-
10 by particularly adapting the same for pas-
senger service.

An object of my invention is the provision of a car coupler particularly adapted for passenger service and formed with locking
15 means comprising a locking and guide block formed as a unitary part inasmuch as a pas-
senger coupler does not require a lock set.

Another object of my invention is the provision of a car coupler in which the locking
20 means therefor is pivoted on an extension from a lock lifter received through an aperture in the lower wall of the head thereof, the front end of said extension being prefer-
ably flush with the front face of the locking
25 means and retained in place by a device such as a cotter, the projecting ends of which are received in pockets or countersunk por-
tions in the front face of said locking means.

Other objects and advantages of the invention relating to the particular arrangement and construction of the various parts will become apparent as the description proceeds.

Referring to the drawings illustrating my invention, the scope whereof is defined by the appended claims:

Figure 1 is a plan view of a coupler, embodying my invention, shown partially in horizontal section for the purpose of more clearly illustrating the locking block.

Figure 2 is a vertical sectional view on the line 2—2 of Figure 1 looking in the direction of the arrows.

Figure 3 is a horizontal sectional view on the line 3—3 of Figure 2 looking in the di-
45 rection of the arrows.

Figure 4 is a partial end elevation and partial transverse sectional view on the line 4—4 of Figure 3 looking in the direction of the arrows.

50 Referring to the drawings in detail, like

parts being designated by like reference characters, there is shown a coupler 1 which is particularly adapted for passenger service in that it has a bottom-operated lock 2 vertically movable in a head 3. Said head is 55 provided with a knuckle 4 swingingly mounted with respect thereto by means of a preferably headless pin 5 passing through a vertical aperture 6 in the knuckle 4 and corresponding registering apertures 7 in the 60 upper pivot lug or ear 8 and lower pivot lug or ear 9 of the head. The knuckle 4 is, as usual, provided with a tail 10 received, when in locked position, in a pocket in the head 3.

The locking mechanism for the knuckle 4, 65 in the present embodiment, comprises the locking block 2 which may be considered as a combination locking block and guide block in that it has a guide flange or rib 11 normally received behind a corresponding flange or rib 12 projecting from the knuckle side of the inner face of the head in front of the rib 11, thereby providing a groove or pocket 13, between the rib 12 and the rear wall of the coupler head, receiving said rib 11. The 70 guard arm side of the locking block 2 is merely guided at its side and rear by engagement with the inner face of the guard arm wall 14 and the rear wall or flange 15 of the head 3.

The locking block 2 is movable upwardly and downwardly by means of a lock lifter 16 passing through an aperture 17 in the lower wall or floor 18 of the head 3 and received in a corresponding groove or pocket 19 in 85 the rear face of the locking block 2. At the upper end of the lock lifter 16, a preferably tapered projection 20 is provided extending forwardly and normally received in a corre-
sponding aperture 21 in the locking block 2 90 for the pivotal mounting of the latter on said lock lifter 16. The front end of the extension 20 is preferably substantially flush with the front face of the locking block 2 and disengagement between the same is preferably prevented by retaining means such as a cotter 22 inserted through a corresponding aperture near the front end of said extension 20 with the ends thereof received in correspond- 100

ing pockets or countersunk portions 23 in the front face of the locking block 2.

For actuating the knuckle 4, I have provided a knuckle opener 24 involving, in the present embodiment, a hub portion 25 receiving a substantially horizontal pivot pin 26, the ends of which are received in corresponding apertures in adjacent portions of the head 3, whereby said opener is pivotally mounted with respect thereto. It will be apparent that said opener 24 is advantageously mounted in the head by positioning the same and then inserting the pivot pin 26 before the knuckle 4 is pivotally mounted with respect to the head. In the present embodiment, it will be apparent that, after insertion of the pin 26 in place, and connection of the knuckle 4 to the head, said pin will be retained in position and prevented from loss by engagement with said knuckle. Said opener 24 is preferably in the form of a modified bell crank lever with an arm 27 projecting over the locking block 2 and engaging a notched portion 28 in the top face thereof upon said locking block being raised to unlocking and knuckle opening positions. The other arm 29 of the knuckle opener 24 is preferably angular, as illustrated, with the lower end thereof positioned outwardly of the tail 10 of the knuckle 4 and, when the knuckle is in locked position, received in a corresponding pocket 30 in the knuckle side of the head 3.

Inasmuch as the particular embodiment of my invention illustrated is especially adapted for passenger service where the pivot pin for the knuckle has to be inserted and withdrawn from the bottom of the coupler on account of the projection of the passenger buffer 40 which prevents taking the pin from the top, said pin is preferably of the headless type and the top thereof is normally approximately flush with the top of the pivot lug or ear 8. The bottom of said pin is preferably provided with a transverse aperture 31 through which and corresponding registering apertures 32 in the lower pivot lug 9 of the head, retaining means 33 is inserted, said means desirably taking the form of a split key, as illustrated. Said key may be inserted through the forward aperture 32 and, when in place, the ends 34 thereof may be expanded into a corresponding pocket 35 in the lower pivot lug 9 of the coupler, whereby all danger of loss thereof is prevented.

For operating the lock lifter 16, a bell crank lever 36 is provided, desirably mounted between pivot lugs 37 on the head by means of a pivot pin 38 extending through said lugs 37 and an intermediate portion of said lever 36. The pin 38 is desirably prevented from loss by means of a head 39 at one end and a cotter 40 extending through the opposite end thereof.

Said lock lifter 16, at its lower end, extends between bifurcated portions 41 of the lever

36 and is pivotally connected thereto as by means of a rivet 42 extending through corresponding apertures in the associated ends of the lock lifter 16 and bell crank lever 36. For protecting the lower end of the lock lifter 16 and the cooperating end of the bell crank lever 36, a shield 43 is desirably provided extending downwardly as an integral projection from the bottom of the coupler head and desirably formed as a transverse web portion 44 reinforced and braced with respect to the lower wall 18 of the head by means of a longitudinal web or gusset portion 45. The opposite end of the lever 36 is adapted for actuation in any desired manner as by connection with a pull rod 46 as will be understood.

The operation of the embodiment of my invention illustrated is as follows. The drawings show the coupler with the knuckle held in locked position and the tail 10 thereof engaging a side of the locking block 2, which side is preferably sloped upwardly and toward the guard arm side of the head as indicated at 47, whereby creeping thereof is prevented in a well known manner. Upon pulling the rod 46, the lower end of the bell crank lever 36 is raised which, in turn, raises the lock lifter 16 to which it is pivotally connected. Upon raising the locking block 2 sufficiently, not only is the tail of the knuckle 4 released, but the knuckle opener is engaged by the notched portion 28 of the locking block and the kicker portion or lower end thereof engages and pushes the tail of the knuckle sideways and outwardly to open the same.

From the foregoing disclosure, it will be apparent that I have devised a car coupler especially adapted for passenger service although, as is obvious, it is not limited to such use. The lock and guide, being of one piece, are preferably placed in the head by insertion through the front opening thereof and provision is made to hold them back in place or, in other words, prevent forward displacement. The lock lifter, passing through the bottom of the coupler, has an extension on its forward portion on which the lock is positioned and the cotter, at the front thereof, holds the lock in its proper place and prevents forward dislodgement.

The pivot pin for connecting the knuckle and head is adapted for withdrawal from the bottom of the coupler when it is desired to replace the knuckle because of the projection of the passenger buffer which prevents taking the knuckle pin from the top. To retain this headless knuckle pin in place, a form of split key is employed which is conveniently inserted and efficiently locks the pin in position, whereby, not only is the pin protected from loss, but rotation in the coupler lugs is prevented and wearing of the holes in the lugs and consequent decrease in the life of the coupler is obviated.

It is very desirable that a passenger coupler

can be operated from the side by a pull rod and provision has been made for operating the present form of coupler by using a straight rod 46 without any offsets either laterally or vertically. When using this form of coupler, the bending of such pull rods is avoided to clear safety chains as the lock lifter is far enough rearward so that the straight rod will give ample clearance with respect to such chains. Except as specifically described, the present form of coupler may correspond substantially with the form of coupler described in my application, Serial Number 107,150, filed May 6, 1926, now Patent No. 1,789,659, dated January 20, 1931, and relating to a form of coupler particularly adapted for freight service, except, of course, the upper wall of the head, above the locking device, need not be provided with an aperture for receiving operating means. It will be also appreciated that the notched portion 28 on the front of the combined locking and guide block functions in a manner similar to that performed by the corresponding notch on the locking block of my referred to application and economizes space, thus making it possible to decrease the height of the head.

Having now described my invention, I claim:

1. In combination, a coupler head, a knuckle pivotally mounted thereon, a locking device for said knuckle comprising a block guided for vertical movement in said head, a lock lifter extending through an aperture in the lower wall of said head and formed with a pivot at its upper end, said pivot being receivable in a corresponding aperture in the locking device for pivotally mounting the same with respect to said lifter, and retaining means connected to the front end of said pivot and projecting to either side thereof for preventing displacement of said locking device with respect to said lifter, the front face of said locking device being formed with pockets receiving the lateral projections of said retaining means.

2. In combination, a coupler head, a knuckle pivotally mounted with respect thereto, a locking block for said knuckle, a lock lifter extending upwardly through an aperture in the lower wall of the head and formed with a tapered projection at its upper end received in a corresponding aperture in the block, the front end of said projection being substantially flush with the front face of said block and cotter means inserted through said front end with projecting ends receivable in pockets in the front face of said block.

3. In combination, a coupler head, a swinging knuckle, a locking block for said knuckle, means for actuating said block comprising a lifter passing through the bottom wall of the

head and provided with a pivot extending longitudinally of the head for pivoting the lifter to said block, a bell crank lever pivotally mounted at the side of said head with one arm pivotally connected to the lower end of the lifter and the other connected to a pull rod for the operation thereof.

4. In combination, a coupler head, a swinging knuckle, a locking device for said knuckle, said device being provided with a pocket in the rear face thereof for receiving a lifter and an aperture extending forwardly therefrom for receiving pivotal means thereon, and a lifter with a pivotal extension, the axis of which is longitudinal, snugly received in said aperture, whereby pivotal movement is permitted between the locking device and lifter in a lateral direction only.

5. In combination, a coupler head, a knuckle pivoted thereto, a lock mounted for vertical movement in said head, a knuckle opener pivoted to swing in the head about a generally longitudinal axis and provided with an arm actuated by the lock upon upward movement, a lifter extending through the bottom of said head and provided with a longitudinally extending pivot portion normally received in a corresponding aperture in said lock whereby said lifter is adapted to angle laterally of the head, a bell crank lever pivotally mounted at a side of the head and provided with an arm extending beneath said head and pivotally connected to the lower end of the lifter, and a pull rod connected to the other arm of said lever for the actuation thereof.

6. In combination, a coupler head, a knuckle pivoted thereto, a lock guided in said head for normally vertical movement, a knuckle opener with an arm normally overlying a portion of said lock for operation upon upward movement of the latter, and another arm depending to the side of the knuckle tail, means extending longitudinally of the head for pivotally mounting said opener above the normal position of the lock to adapt said depending arm for lateral swinging to effect actuation of the knuckle, a lifter extending through the bottom of said head, and a bell crank lever pivotally mounted at a side of said head and provided with an arm extending beneath said head and pivotally connected to the lower end of the lifter, the upper end of said lifter being provided with a pivot portion extending longitudinally of the head for pivotal connection with the lock to allow for the necessary angling of the lifter, as it is moved by the bell crank lever, without causing the lock to bind in the guiding portion of the head.

WILLARD F. RICHARDS.
